UNITED STATES PATENT OFFICE.

WALTER EVERETT MOLINS, OF LONDON, ENGLAND.

AUTOMATIC CIGARETTE-PACKING MACHINE.

Application filed October 6, 1924, Serial No. 742,048, and in Great Britain October 26, 1923.

This invention relates to automatic machines for packing cigarettes and articles of similar shape in block bottom, open mouth packets.

5 It has been proposed in machines of this class to employ a compartment wheel, the packet being formed in one compartment thereof from cut blanks by means of a former plunger and tucking mechanism, the 10 sides of the packet being folded but not positively secured, the wheel then being rotated to bring the packet into the filling position and the filled packet discharged and sealed by the application of an adhesive 15 stamp. Such a machine may also operate on previously gummed blanks so that a packet having closed and gummed side folds is presented to the filling mechanism.

The present invention has for its object 20 to provide a machine which is capable of long runs at high speed. According to the invention the machine is of the type in which the packets are made by former mechanism and are filled before the side folds are 25 secured by an adhesive. The machine is fitted with improved mechanism for feeding the blanks rapidly to the packet forming mechanism and for transferring the unsealed packets to the filling mechanism, with 30 an improved method of applying adhesive to the folded sides of the filled packet and also with improved mechanism for transferring the filled and gummed packets from the machine.

35 The improved transfer mechanism comprises pairs of continuously rotating members which may be discs, between which the packet is gripped and held. The filling mechanism is preferably of the known oscillating funnel type operating in conjunction with an endless conveyor having pusher pieces or some similar apparatus.

40 During the filling operation the packet is held between the rotating discs, the latter slipping past the packet as hereinafter described.

The use of continuously rotating transfer members increases the working speed of the machine since it obviates the use of reciprocating or intermittent mechanism such as 45 is usually employed, which is, of necessity, slower in its action. After the filling operation, the folded sides of the packet are lifted or opened so that gum may be applied 50 along the full length of the side folds. This length includes a portion of the outside of

printed face of the blank which, in folding, becomes folded inside. When gumming takes place before forming, this portion does not receive gum. Thus by the present 60 method of exposing the whole length of the sides to the gumming apparatus the packet is more securely and neatly sealed.

This filled and sealed packet is finally ejected by the continuously rotating transfer members at a high rate of speed.

The machine is particularly adapted for packing a single row of cigarettes, a row of five for example, in a small tightly fitting packet made from a single sheet or blank.

To enable the invention to be fully understood it will now be described by reference to the accompanying drawings in which:

Fig. 1 is a side elevation of the packet forming end of the machine, and

Fig. 2 is a similar view of the other end of the machine.

Fig. 2^a is an end view of the packet making mechanism shewn in Fig. 1.

Figs. 1 and 2 if placed together meet on 80 the line A—A giving a view of the whole machine.

Fig. 3 is a plan view of Fig. 1 with the packet forming mechanism removed.

Fig. 4 is a plan view of Fig. 2 shewing the 85 filling portion of the machine only.

Figs. 3 and 4 if placed together meet on the line B—B giving a plan view of the whole machine.

Fig. 5 is a sectional elevation of a packet 90 blank feeding device shewing a method of feeding the packet blank into the machine, and

Fig. 6 is a view of a detail of the packet blank feeding mechanism for use with packets having irregular tops.

Figs. 7 and 8 are views of details of the mechanism for transferring the empty packet to the machine bed.

Figs. 9, 10 and 11 are views of details of the packet folding operations.

Figs. 12, 13, and 14 are views of details of the mechanism for delivering the filled packets, drawn to a larger scale.

Figure 15 is a view of a detail for dealing 105 with cigarettes in the event of failure of the packeting portion of the apparatus.

Figs. 16, 17, 18, 19 are views of details of mechanism for filling the packets.

Referring first to Figs. 1-4: The packet 110 forming mechanism is mounted on a frame secured to the machine bed α and com-

prises a reciprocating plunger 4 on which the packet is formed and stripped therefrom in the known manner.

The plunger 4 is guided by rollers 5 and a slide 6 and is reciprocated between a pair of parallel jaws 7 by any suitable means such, for example, as by a rod 15 attached at its lower end to a connecting rod arranged at the back of the machine and operated by a crank driven from the source of power (not shewn). In operation the plunger 4 rises clear of the jaws 7, as shewn in Fig. 1, but for an exceedingly short time only and during this time the blank for making the packet is fed across the top of the jaws at A (Fig. 1). The packet blank is a sheet of paper or the like and is preferably fed from a stack, but if desired it may be cut from a reel or continuous web by any suitable means.

The improved mechanism for feeding the blanks into position over the top of the jaws 7 is shewn in Fig. 5.

This mechanism is mounted on portions of the frame 1 adjacent to the jaws 7 and comprises a pair of rollers 2 which are rotated at uniform speed and a pair of rollers 3, 8, the roller 3 rotating at a high speed, the roller 8 being merely a follower. The roller 8 is mounted on a swinging lever 10, one end of which is secured to a rocking spindle 11 carried in a bearing 12 and projecting to the back of the machine, the arrangement being such that the roller 8 is brought momentarily into contact with the roller 3 at certain desired moments.

With this arrangement, the blank 9 is fed by the main feed rollers 2 to the rollers 3, 8, and as the latter is brought into contact with the high speed roller 3, the blank receives a sharp impulse which delivers it into position over the jaws 7 at the moment that the plunger 4 leaves the jaws and just before its return stroke.

The operation of the roller 8 is controlled in synchronism with the movement of the plunger 4 by the following means.

The rod 15 which operates the plunger 4 is fitted with a striking piece 14 which is adapted to engage a pawl 13 on one end of the spindle 11.

As the rod 15 rises, carrying the plunger clear of the jaws 7, the striking piece 14 lifts the pawl 13 and rocks the lever 10, bringing the roller 8 into contact with the roller 3 and causing the blank to be fed under the plunger.

A spring 15^a returns the parts to the original positions as the rod 15 moves down again.

The blank 9 is guided into position beneath the plunger 4 by a channel 16 fitted with narrow strips 17 at each side. A stop 18 is arranged to check the forward travel of the blank and any rebound is checked by the ends 19 of the strips 17.

When the blank is in position beneath the plunger 4, the plunger descends and carries the blank through the folding and stripping mechanisms and forms a packet open at one end in the known manner, but in this case the blanks are free from adhesive and the packet is not gummed.

The packet on being stripped from the plunger is held in the channel 20 (Fig. 1) which forms a continuation of the jaws 7, and is pushed downwards by the next packet and so on.

Since the packets are not gummed they tend to spring open, creating sufficient friction to retain them in the desired positions.

In some types of packets the open end is shaped so that the sides are not all of the same length, which causes the packets to telescope or crumple as they are pushed down the channel 20.

In Fig. 6 a packet C is shewn having a curved or shaped open end with a flap C' and in order to prevent the crumpling above referred to the plunger 4 is fitted with two projecting arms 21 having spring pawls 22 at their ends. These pawls 22 as shewn, catch the narrow sides of the packet, which are of equal length, and thrust it down the full length of the channel 20 to the transfer mechanism.

With the plunger as shewn in Fig. 1, after several packets have been made, the lowest packet projects from the channel 20 and enters the transfer apparatus.

The transfer apparatus (Figs. 1, 4, 7 and 8) consists of a wheel comprising a pair of rotating discs 23, 24, one or both of which are preferably of transparent material such as glass to enable the operations to be observed. These discs are mounted on a spindle 30 rotating in a bearing 31 and are spaced apart sufficiently to grip the packet lightly between them carrying it round without distortion.

To prevent displacement of the packet as it enters the wheel a guide plate 25, mounted on a link 26 pivoted at 27 is provided, the link being oscillated by a roller 29 thereon which engages a cam 28 on the spindle 30 (Fig. 1). As the packet enters the wheel the plate 25 is moved inwards towards the wheel centre and forms a guide channel with a fixed guide piece 24^a which prevents the packet from being displaced. This guide piece is preferably secured to the channel 20 as shown in Figure 1.

If desired notches or stops may be provided on the insides of the discs 23, 24, to locate the packet in the correct position.

A packet K, entering the wheel, takes up the position shewn at L, Fig. 7, and is carried by the discs into the position D, being brought into contact with a stripper 30^a pivoted at 30^a to the lower end of the guide 24^a, the leading end of the packet meeting a fixed

piece 33^a in which is hinged a spring stop 32. The stripper is operated by a cam 31^a on spindle 30 through the medium of the cam roller 32' to press the packet K flat upon the 5 machine bed, and is fitted with a projection 33 so that in the final position as shewn in Fig. 8, the packet K is flat upon the bed and the projection 33 has depressed the spring stop 32 to form an abutment for the packet. 10 The bed beneath the mouth of the packet is preferably provided with a depression as hereinafter described.

It is in this position that the packets are filled with cigarettes.

15 The cigarettes are fed down a chute 35 by any suitable means, such for example as by a vane hopper feed, and pass on to the filling portion of the machine bed 35^a. The filling portion of the bed is fitted with a central slot in which the pusher pieces 34 (one only being shewn) of an endless conveyor pass beneath the chute 35 and carry away the desired group of cigarettes in the known manner. 20

25 The cigarettes are carried by the conveyor between guides 35^b into a mouthpiece 36 (Fig. 1) shewn more clearly in Figs. 16-18. This mouthpiece is funnel-shaped and may be of a rigid nature instead of the 30 usual spring tapered type since as the packet is not gummed it is unnecessary to compress the cigarettes as in cases in which they have to be forced into a more rigid gummed packet.

35 The mouthpiece 36 is mounted on a sliding carriage 37^a guided at one side on a rod 38 secured to the machine bed and on the other side by a roller 39 running on a guide strip 39^a on the bed. The carriage 37 is reciprocated by means of a bell crank lever 40, pivoted at 41 and carrying at one end a roller 42 working in a slotted guide 42^a on one side of the carriage, the other end of the lever 40 carrying a roller 43 driven by a 40 suitable cam 44.

The carriage is moved forwards by the cam 44 against the action of a spring 45 as will be understood. The bed is slotted to allow the mouthpiece to slide and the underside of the mouthpiece is also slotted to allow the pusher pieces 34 to pass in the known manner.

It will be understood that the cigarettes are pushed into the mouthpiece 36 and the latter is introduced into the open mouth of the packet while the latter is held by the stop 32 in the transfer wheel in the position shewn in Fig. 8.

In Figs. 16-18 the filling operation is 55 shewn more clearly. In these figures it will be noted that a depression M is preferably formed in the bed beneath the open end of the packet K which as the mouthpiece 36 enters the packet, allows the mouth of the 60 packet to bell downwards as clearly shewn

in Fig. 16, thus giving a free entrance for the cigarettes and enabling them to be pushed therein without any previous compression. Fig. 19 is a view of the open end of the packet at this stage. 70

The mouthpiece is provided with a guide 90 to prevent rising of the cigarettes and also with a guide plate 91 to prevent the cigarettes from falling through the slot 92 in the bed in which the mouthpiece oscillates. 75

Fig. 16 shews the parts in position at the commencement of the filling operation and Fig. 18 in position after the filling has been completed, the stop 32 being raised, to allow the packet to pass beneath by the operation 80 of the transfer wheel as will be understood from the previous description with reference to Fig. 8.

The filled packet is then carried by the conveyor beneath the stop 32 and under a plate 45^a (Figs. 1, 9, 10, 11) carrying a pair of folders 53 having spiral surfaces. Another pair of folders 46 are mounted on the machine bed. Between the two pairs of folders a pair of gum wheels 50 are arranged, which dip into a gum bath 51 and project into contact with the lower edges of the sides of the packet. Adjustable spring controlled scrapers 52 are provided for removing surplus gum. 85 90 95

As shewn in Fig. 11 as the packet meets the first pair of folders 46, the latter lift up the top folds or flaps 46^b of the packet, allowing the gum wheels to apply gum to the folds or flaps underneath. The packet then passes to the folders 53 which press the top fold down on to the gummed fold beneath, thus securing the sides and end of the packet. 100

Guide pieces 46^a are screwed to the top plate 45^a and assist in controlling the packet 105 as it enters between folders 46.

By gumming the packet after forming as above described the whole length of the side folds or flaps are gummed. This length includes a portion of the outside or printed 110 face of the blank which, in folding, becomes folded inside. When gumming takes place before forming this portion does not receive gum. Thus by the present method of exposing the whole length of the sides to the 115 gumming apparatus the packet is more securely and neatly sealed.

After passing between the folders 53 the packet passes into a delivery wheel.

This wheel (Figs. 2, 12, 13, 14) consists 120 of a pair of discs 54, which may be of metal, and somewhat similar to the discs of the transfer wheel. The discs 54 rotate on a spindle 54^a and grip the filled packet between them carrying it down towards an 125 ejector.

The ejector comprises a plate 55 pivoted at 56 and oscillated by a cam 57 on the spindle 54^a through the roller 58 mounted on a screw fixed to a prong 77 attached to ejector 130

plate 55 against the tension of a spring 59. The plate moves inwards between the discs 54 and then outwards into a stacker 60. On moving inwards the plate 55 removes a packet and then moving outwards under the action of its cam delivers the packet to the stacker and pushes it along the bottom 60 until the packet is beyond spring non-return catches 61 on the sides of the stacker which prevent its return.

The packets are thus pushed along the stacker at each stroke of the ejector and are either gathered up by the operator or taken up by the conveyor of a boxing apparatus of any known kind, or dealt with in any other desired manner.

If the packets are to be closed at the top they may be ejected into a suitable sealing machine.

Packets of the kind shewn in Fig. 6, for example, may be ejected into a flap turning apparatus which folds and tucks the flap C.

The sides of the stacker are heated by electric or other heaters 62^a and in order to relieve the pressure on the packets one or both sides of the ejector may be opened by a cam at each stroke of the ejector. In the example illustrated (Figs. 2, 12, 14) one side 67 of the stacker is movable, being fitted with two long arms 68, each pivoted at 69 to the main frame of the stacker.

A rod 64 pivoted at 65 at one end is connected by a pin 66 to the side 67, the other end of the rod carrying a roller 63 engaging a crown cam 62 on the spindle 54^a (Fig. 12).

With this arrangement, at every stroke of the ejector a movement of the side 67 is obtained which relieves the pressure on the packets and allows the ejector to move them easily.

It may sometimes happen that a bunch of cigarettes is carried to the mouthpiece 36, and owing to the failure of the packet blank feed for example, no packet is ready in the transfer wheel to receive them. In this case the cigarettes pass along to the delivery wheel without causing any trouble, but in order to prevent the possibility of jamming in the stacking apparatus, it is necessary to remove them before delivery. Mechanism for effecting this object is shewn in Figs. 12, 13 and 14.

A sharp edged pawl 70 is pivoted on a spindle 76 over the channel along which the packets pass adjacent to the delivery wheel and is normally held slightly below the level of the top of a filled packet K by a spring 71.

If a filled packet meets the pawl 70, the latter is lifted and rides lightly over the packet without damaging it. If, however, a bunch of cigarettes meets the pawl, the latter drops down between the cigarettes as shewn in Fig. 15.

As shewn best in Figs. 12 and 14 an arm

81 is secured to the spindle 76 and carries a pin 82 on which a hook shaped lever 73 is pivoted, the hook normally engaging a stop lever 74 held by a spring 75 and pivoted at 75^a.

If the pawl 70 drops, the lever 73 also drops releasing lever 74 which under the action of the spring 75 is oscillated about its pivot causing its other end to fall, engaging the prong 77 on the ejector plate 55.

This prevents further inward movement of the ejector plate and leaves a space through which the loose cigarettes fall undamaged into a collector box, (not shewn).

If the next group of cigarettes is packed the pawl 70 is raised and the hook on lever 74 moves into position to re-engage with the stop lever 74, as soon as the latter is lowered. This lowering of the lever 74 is effected by a cam 78 on the back of one of the discs 54 which engages a roller 79 on the lever 74 swinging the lever about its pivot into the desired position. The ejector plate can then travel through its full stroke and eject the packet.

The delivery wheel may be provided with a hinged cover 80 to prevent packets being thrown outwards by the ejector. The hook 73 is free on the pin 82, but is controlled by a torsion spring 83^a which twists it in a clockwise direction, a tail 73^a on the hook engaging the spindle 76 to limit the motion of the hook. This arrangement gives flexibility to the action and ensures that the hook 73 will always operate correctly.

The hook 73 can only disengage from the stop lever 74 when the roller 79 is lifted by the cam 78. This action is timed to take place when a group of cigarettes is beneath the pawl 70.

It will be understood that various modifications may be made without departing from the spirit of the invention.

The blanks may be heated during forming to assist in the final drying or they may be gummed before forming and finally closed and dried after filling.

The filling operation may be effected by a plunger apparatus instead of the conveyor apparatus hereinbefore described.

If desired the packet blank feed may be fitted with creasing apparatus.

While the invention has been described with reference to filling a packet with a single row of cigarettes it will be understood that it is not so limited as the apparatus may be readily modified to operate with several rows of cigarettes. Also while the packet blank has been described as a single sheet, it may also consist of a double sheet, an outer cover and an inner wrapper for example, suitable means being employed for feeding the double sheet to the packet forming apparatus.

Having thus described the nature of my

said invention and the best means I know of carrying the same into practical effect, I claim:—

1. In an automatic machine of the type forming an open mouth block bottom packet from blanks fed thereto, means for transferring the packets to the filling position comprising continuously rotating members between which the packet is gripped, and means for retaining the packet in the filling position while permitting the transfer members to slip past the packet.
2. In an automatic machine of the type forming an open mouth block bottom packet from blanks fed thereto, means for transferring the packets to the filling position comprising continuously rotating members between which the packet is gripped, and means for retaining the packet in the filling position while permitting the transfer members to slip past the packet, said retaining means comprising a movable stop against which the closed end of the packet rests while said packet is being filled.
3. In an automatic machine of the type forming an open mouth block bottom packet from blanks fed thereto, a channel for receiving the formed unsealed packets, continuously rotating members for transferring the packet to the filling position, a guide between the continuously rotating members, a reciprocating plate for pushing the unsealed packet into contact with the guide, a machine bed for receiving the packet for filling, a pivoted stripper periodically operated to press the packet flat on the machine bed, and mechanism for retaining the packet in the filling position while permitting the rotating members to slip past the packet.
4. In an automatic machine of the type forming an open mouth block bottom packet from blanks fed thereto, a channel for receiving the formed unsealed packets, continuously rotating members for transferring the packet to the filling position, a guide between the continuously rotating members, a reciprocating plate for pushing the unsealed packet into contact with the guide, a machine bed for receiving the packet for filling, a pivoted stripper periodically operated to press the packet flat on the machine bed, and mechanism for retaining the packet in the filling position while permitting the rotating members to slip past the packet, said retaining mechanism comprising a movable stop against which the closed end of the packet rests while said packet is being filled.
5. In an automatic machine of the type forming an open mouth block bottom packet from blanks fed thereto, a machine bed for receiving the formed packet blank for filling, an endless conveyor for moving the cigarettes for filling, an oscillating mouth piece for receiving the cigarettes and push-
- ing them into the packet blank, a slot formed within the mouth piece, and pusher elements attached to the conveyor and movable through the slot for enabling the conveyor to push the cigarettes entirely into the packet.
6. In an automatic machine of the type forming an open mouth block bottom packet from blanks fed thereto, a machine bed for receiving the formed packet blank for filling, an endless conveyor for moving the cigarettes for filling, an oscillating mouth piece for receiving the cigarettes and pushing them into the packet blank, a slot formed within the mouth piece, and pusher elements attached to the conveyor and movable through the slot for enabling the conveyor to push the cigarettes entirely into the packet, said mouth piece comprising a rigid member through which the cigarettes are passed without compression.
7. In an automatic machine of the type forming an open mouth block bottom packet from blanks fed thereto, a machine bed for receiving the formed packet blank for filling, an endless conveyor for moving the cigarettes for filling, an oscillating mouth piece for receiving the cigarettes and pushing them into the packet blank, a slot formed within the mouth piece, and pusher elements attached to the conveyor and movable through the slot for enabling the conveyor to push the cigarettes entirely into the packet, said machine bed being provided with a depression beneath the mouth of the packet to permit yielding of the packet during filling.
8. In an automatic machine of the type forming an open mouth block bottom packet from blanks fed thereto, means for filling the packet, means for causing travel of the packet forward, and a folder mechanism for receiving the filled ungummed packet and opening the folded sides of the packet to allow adhesive to be applied thereto.
9. In an automatic machine of the type forming an open mouth block bottom packet from blanks fed thereto, means for filling the packet, means for causing travel of the packet forward, a folder mechanism for receiving the filled ungummed packet and opening the folded sides of the packet to allow adhesive to be applied thereto, and adhesive applying mechanism comprising a pair of gum wheels and carrying means to convey the unfolded sides of the packet in proximity to the wheels for permitting application of adhesive.
10. In an automatic machine of the type forming an open mouth block bottom packet from blanks fed thereto, means for filling the packet, means for causing travel of the packet forward, a folder mechanism for receiving the filled ungummed packet and opening the folded sides of the packet to al-

low adhesive to be applied thereto, means to apply adhesive to the unfolded sides of the packet, and a folding device for pressing the unfolded and gummed sides together.

5 11. In an automatic machine of the type forming an open mouth block bottom packet from blanks fed thereto, a receptacle for the completed packet, and a delivery mechanism comprising a pair of rotating elements for 10 gripping the packet and passing it to the receptacle.

12. In an automatic machine of the type forming an open mouth block bottom packet from blanks fed thereto, a receptacle for the completed packet, a delivery mechanism comprising a pair of rotating elements for gripping the packet and passing it to the receptacle, a pivoted ejector plate fitted between the rotating elements, and means for periodically oscillating said plate to receive the 20 packet from the rotating elements and to deliver it to the receptacle.

13. In an automatic machine of the type forming an open mouth block bottom packet from blanks fed thereto, a receptacle for the completed packet, a delivery mechanism comprising a pair of rotating elements for gripping the packet and passing it to the receptacle, a pivoted ejector plate fitted between the rotating elements, means for periodically oscillating said plate to receive the packet from the rotating elements and to deliver it to the receptacle, a channel within the receptacle for receiving the completed 35 packet, and spring catches within the channel for preventing return of a packet after delivery to the channel.

14. In an automatic machine of the type forming an open mouth block bottom packet from blanks fed thereto, a receptacle for the completed packet, a delivery mechanism comprising a pair of rotating elements for gripping the packet and passing it to the receptacle, a channel within the receptacle for receiving the completed packet, said channel having a movable side, and mechanism for moving said side on each packet delivery stroke for the purpose of relieving pressure 45 on the packets in the channel.

50 15. In an automatic machine of the type forming an open mouth block bottom packet from blanks fed thereto, means for filling the packet blank with cigarettes, means for causing forward travel of the packet mechanism for unfolding, gumming, and refolding the sides of the filled packet, a receptacle for receiving the completed packet, and means for preventing delivery of an unpacketted group of cigarettes to the receptacle.

60 16. In an automatic machine of the type forming an open mouth block bottom packet from blanks fed thereto, a receptacle for the completed packet, a delivery mechanism comprising a pair of rotating elements for

gripping the packet and passing it to the receptacle, a pivoted ejector plate fitted between the rotating elements, means for periodically oscillating said plate to receive the packet from the rotating elements and to deliver it to the receptacle, and mechanism for preventing delivery of an unpacketted group of cigarettes. 70

17. In an automatic machine of the type forming an open mouth block bottom packet from blanks fed thereto, a receptacle for the completed packet, a delivery mechanism comprising a pair of rotating elements for gripping the packet and passing it to the receptacle, a pivoted ejector plate fitted between the rotating elements, means for periodically oscillating said plate to receive the packet from the rotating elements and to deliver it to the receptacle, a movable stop for preventing inward motion of the oscillating plate, a movable cam interposed in the path of the completed packet, normally resting on the packet and adapted to move downward between the cigarettes of an unpacketted group, and connections actuating the movable stop on downward motion of the movable cam. 80

18. In an automatic machine of the type forming an open mouth block bottom packet from blanks fed thereto, automatic feeding means for delivering the packet blank to the packet forming mechanism, and mechanism for periodically imparting a sharp impetus to the blank towards the end of its travel into the forming mechanism, means for forming the packet, and a continuously rotating device for receiving the packets and transferring them to a filling position, means for filling the packets, and means for supplying adhesive to the mating edges of said packets. 95

19. In an automatic machine of the type forming an open mouth block bottom packet from blanks fed thereto, a pair of rollers rotating at uniform speed for feeding the blanks, a high speed roller beneath which the blanks are fed from the uniform speed rollers, an oscillating follower roller for pressing the blank in contact with the high speed roller at periodic intervals, whereby the blank is shot into the forming mechanism, means for forming the packet, and a continuously rotating device for receiving the packets and transferring them to a filling position, means for filling the packets, and means for supplying adhesive to the mating edges of said packets. 110

20. In an automatic machine of the type forming an open mouth block bottom packet from blanks fed thereto, a pair of rollers rotating at uniform speed for feeding the blanks, a high speed roller beneath which the blanks are fed from the uniform speed rollers, a follower roller for pressing the blank in contact with the high speed roller, 125

an oscillatable lever on which the follower 5 roller is mounted, a spring held lever operatively connected to said oscillatable lever, and a cam mounted on the blank forming plunger for periodically actuating the spring held lever, whereby the blank is shot into the forming mechanism at the proper moment, means for forming the packet, and a continuously rotating device for receiving the 10 packets and transferring them to a filling position, means for filling the packets, and means for supplying adhesive to the mating edges of said packets.

21. In combination with an automatic 15 machine for forming an open mouth block bottom packet from blanks fed thereto, a channel for receiving the formed unsealed packet, a transfer mechanism for transferring the formed packets to the filling position, and means for positively feeding the 20 packet through the channel to the transfer mechanism.

22. In combination with an automatic 25 machine for forming an open mouth block bottom packet from blanks fed thereto, a channel for receiving the formed unsealed packet, a transfer mechanism for transferring the formed packets to the filling position, and means for positively feeding the 30 packet through the channel to the transfer mechanism, comprising arms operatively connected to the forming mechanism, and

pivoted pawls attached to said arms for making contact with the sides of the packet and pushing it to the transfer mechanism. 35

23. A packing machine which comprises in combination means for forming an open mouth block bottom packet from a strip of wrapping material fed thereto, a continuously rotating device arranged to receive the 40 packets so formed and transfer the same to a filling position, means for automatically filling said packets with the contents to be packed and means for supporting the packet against the movement of the contents as the 45 same are being inserted therein.

24. In an automatic machine of the type forming an open mouth block bottom packet from blanks fed thereto, a receptacle for the completed packet, and a delivery mechanism 50 comprising a pair of elements, rotating in parallel planes for gripping the packet and passing it on to the receptacle.

25. In an automatic machine of the type forming an open mouth block bottom packet 55 from blanks fed thereto, a receptacle for the completed packet, and a delivery mechanism comprising a pair of coaxial rotating elements for gripping the packet between their opposing faces and passing it on to the receptacle. 60

In testimony whereof I have signed my name to this specification.

WALTER EVERETT MOLINS.
